(57) **CLAIM**

The ornamental design for a lid for beverage container, as shown and described.

DESCRIPTION

FIG. 1 is a top view of a lid for beverage container showing my new design according to a first embodiment;

FIG. 2 is a bottom view thereof;

FIG. 3 is a front view thereof;

FIG. 4 is a rear view thereof;

FIG. 5 is a left side view thereof;

FIG. 6 is a right side view thereof; and

FIG. 7 is a perspective view thereof;

FIG. 8 is a top view of a lid for beverage container showing my new design according to a second embodiment;

FIG. 9 is a bottom view thereof;

FIG. 10 is a front view thereof;

FIG. 11 is a rear view thereof;

FIG. 12 is a left side view thereof;

FIG. 13 is a right side view thereof; and,

FIG. 14 is a perspective view thereof.

The broken lines depict portions of the article forming no part of the claimed design.

1 Claim, 10 Drawing Sheets
